(57) **CLAIM**

The ornamental design for a scale, as shown and described.

DESCRIPTION

FIG. 1 is a front perspective view of the scale showing the new design;

FIG. 2 is a front view of the scale;

FIG. 3 is a rear view of the scale;

FIG. 4 is a side view of the scale;

FIG. 5 is another side view of the scale;

FIG. 6 is a top view of the scale; and,

FIG. 7 is a bottom view of the scale.

The broken line showing is for illustrative purposes only and forms no part of the claimed design.
